UNITED STATES PATENT OFFICE.

SILAS R. DIVINE, OF LOCH SHELDRAKE, NEW YORK, ASSIGNOR TO THE
REND ROCK POWDER COMPANY, OF NEW JERSEY.

PROCESS OF PREPARING EXPLOSIVE COMPOUNDS.

SPECIFICATION forming part of Letters Patent No. 289,755, dated December 4, 1882.

Application filed July 23, 1883. (No specimens.)

To all whom it may concern:

Be it known that I, SILAS R. DIVINE, of Loch Sheldrake, Sullivan county, State of New York, and a citizen of the United States, have 5 invented an Improved Process for Preparing Explosive Compounds, of which the following is a full, clear, and exact specification.

The object of my present invention is to provide a process for uniting the ingredients 10 of an explosive compound when such ingredients consist of a solid ingredient—such as chlorate of potash—and a liquid ingredient—such as nitro-benzole—so that entire accuracy as regards the relative proportions in which 15 said ingredients are united will be at all times attained, even when the combination is effected by an unskilled laborer.

My invention consists of first saturating the solid ingredient of chlorate of potash with a 20 mixture composed of the liquid ingredient of nitro-benzole and a volatile fluid—such as bisulphide of carbon—the proportions of the constituents of said mixture being such that the 25 quantity of nitro-benzole contained in the mixture absorbed by the chlorate of potash in the said saturation will be the proper proportion of the nitro-benzole relatively to the chlorate of potash in the compound, and then allowing the volatile fluid to evaporate and es- 30 cape from the mass.

In determining the proportions of the said constituents of the said mixture, I add to the quantity of the liquid ingredient of the explosive compound, which is the proper proportion thereof relatively to the chlorate of potash in said compound, such a quantity of bisulphide of carbon as will make a fluid volume equal to the total fluid-absorbing capacity of the chlorate of potash—as, for example, I add to the proper proportion of nitro-benzole relatively to the chlorate of potash in the explosive about one-half its volume of bisulphide of carbon, the total fluid-absorbing capacity of chlorate of potash being about one- 45 third more than the fluid volume of said proper relative proportion of the nitro-benzole. It is desirable and intended that the said mixture of the liquid ingredient of the explosive and the said volatile fluid should be had in a 50 convenient vessel, and should be furnished to

the ordinary laborer or unskilled workman who is to effect the combination of the ingredients of the explosive. The workman is then called upon to exercise no discretion or skill in his labor, but simply allows the solid ingredient to absorb and saturate itself with the 55 said mixture, which he accomplishes by permitting the solid to soak in the mixture. It should be understood that the chlorate of potash is employed in a crushed or powdered 60 state; and I find that the saturation of the solid ingredient by the said mixture will be effected in from about twenty minutes to two hours, depending upon the temperature and other conditions of the atmosphere, and upon the 65 diameter of the mass of the solid.

Upon effecting the saturation as above stated, the workman then simply removes the saturated mass of the ingredients from the described mixture and exposes it to the air in 70 any convenient place for a comparatively short space of time—say from about fifteen to forty minutes—when the volatile fluid evaporates and escapes from the mass. The solid and liquid ingredients of the explosive will then 75 be left united in a wet or moist mass, and ready for immediate use as a blasting compound.

It is evident that explosive compounds in which the solid ingredient is perchlorate or permanganate of potash, and in which the 80 liquid ingredient is composed of another liquid nitro compound than nitro-benzole, or of a non-volatile fluid hydrocarbon in a free state, may have their ingredients united by the employment of my described process.

Other volatile fluids than bisulphide of carbon may be employed as the volatile fluid in the herein-described mixture for saturation, the essential condition being observed that said fluid shall possess the quality of rapid 90 volatility at ordinary temperatures, and also that it shall contain nothing which will embarrass or interfere with the operation of the final compound as an explosive.

What I claim as my invention, and desire to 95 secure by Letters Patent, is—

The described process of preparing explosive compounds composed of two ingredients, one a solid—such as crushed or powdered chlorate of potash—and the other a liquid—such as 100

nitro-benzole—which consists in first saturating the chlorate of potash with a mixture of the nitro-benzole and a volatile fluid—such as bisulphide of carbon—the proportions of the 5 constituents of said mixture being such that the quantity of the nitro-benzole contained in the mixture absorbed by the chlorate of potash in said saturation will be the proper proportion of said nitro-benzole relatively to the

absorbing mass of the chlorate of potash in 10 the explosive, and then allowing the said volatile fluid to evaporate and escape from the mass, substantially as and for the purpose specified.

SILAS R. DIVINE.
